UNITED STATES PATENT OFFICE

ARTHUR SCHNEIDER, OF DUSSELDORF, GERMANY, ASSIGNOR TO EUMUCO AKTIEN-
GESELLSCHAFT FÜR MASCHINENBAU, OF LEVERKUSEN-SCHLEBUSCH, GERMANY, A
GERMAN COMPANY

POWER HAMMER

Application filed February 25, 1931, Serial No. 518,220, and in Germany February 27, 1930.

My invention relates to an improved power hammer adapted to be raised by an elastic fluid and to be lowered again in an accelerated manner, and has for its object to reduce the stress to which the piston rod of this hammer is subjected to such an extent that the piston rod will withstand the shock due to the blow without breaking and without being made stronger than is necessary in order to permanently resist the forces during the raising of the hammer.

The invention consists in employing in a hammer of the type described, in connection with one another, a piston rod capable of moving within the tup and a cushion disposed between the piston rod and the tup and adapted to become upwardly and downwardly effective during the motion of the piston rod.

20 By way of example, a power hammer is illustrated in the accompanying drawings, in which Figure 1 is a front view, partly in section, of a power hammer, and Figure 2 is a section of the improved tup.

25 Referring to the drawings, the hammer is shown in Fig. 1 is provided with a frame *a* wherein the tup *b* is vertically guided in the known manner. The tup *b* has a bore *c* through which the piston *d* attached to the lower end of the piston rod *e* can move up and down, the bore *c* being closed on top by a plate. The stuffing box *h* in which the piston rod *e* can be guided effects the permanent air-tight and steam-tight closing of the bore *c*. The duct *c'* connects the space of the bore *c* over the piston *d* with the space of the bore *c* under the piston *d*. To the lower surface of the tup *b* the upper portion *l* of a die may be secured, the lower portion *m* of the die being attached below the tup to the anvil.

30 The upper end of the piston rod *e* carries a piston *i* adapted to move up and down in the cylinder *k* sealed air-tight and steam-tight on top and below and connected with the control valve *p* which is capable of alternately admitting into the upper and lower portion of the cylinder *k* a fluid that is under pressure due, for example, to compressed air or steam. This fluid may be supplied by a pipe, 35 not shown, which is connected at *p'*. The

control valve *p* is automatically moved up and down by means of the rods *o*, and the rods *o'* serve for actuating the control valve *p* by hand or foot. The piston rod *e* and the piston *i* are perforated along the central line of the piston rod *e*. The bore *d'* leads from the bore *e'* in the piston rod *e* through the piston *d* to the duct *c'*. A piping *g* extends from the control valve *p* through the center of the cylinder *k* to the bore *e'* and is packed relative to the cover of the cylinder *k* and the bore *e'*.

40 A curved lever *n* hugs in the usual way a face of the tup *b* and is connected with the control rods *o* and thus with the control valve *p*.

The hammer as shown and described works as follows:

45 When compressed air or steam is supplied from below under the piston *i* by the valve *p*, the piston rod *e* with the piston is raised until the bore *d'* is out of communication with the duct *c'* and the contents—air, compressed air or steam—of the portion of the bore *c* arranged above the piston *d* is compressed 50 to such an extent that its pressure upon the piston *c* is as great as the resistance offered by the tup *b* to its upward motion. The tup *b* is then lifted until the control valve *p* is closed again by the curved lever *n* and the action of the fluid admitted into the cylinder *k* ceases. Simultaneously, compressed air or steam is admitted through the valve *p* into the space above the piston *i*.

55 The piston *i* then descends again with the rod *e* and the tup *b*. When the pressure upon the surface of the piston *i* has increased to the necessary degree, the piston *i* with the piston rod *e* and the piston *d* will move more quickly than the tup *b*, which, however, is counteracted by the fluid flowing through the pipe *g*, the bore *e'*, the bore *d'* and the duct *c'* into the bore *c*. When the piston *d* descends in the bore *c* far enough to shut off the bore *d'* from the duct *c'*, the contents of the bore *c* under the piston *d* are gradually compressed and form a cushion for the motion of the piston rod *e* and the parts connected therewith relative to the tup *b*. If the upper portion *l* of the die strikes the lower portion *m* 60

or a forging disposed between the two die members, the cushion referred to will continue to act and prevent the piston rod *e* from receiving such a hard blow that it will break, 5 it being immaterial whether the first or a subsequent blow is concerned.

The piping *q* may be omitted as in the improved form shown in Fig. 2 which is a section drawn vertically to the frame or stand 10 as illustrated in Fig. 1, the entire hammer being otherwise constructed exactly as shown in Fig. 1. The improved tup *b* shown in Fig. 2 has two bores *g* and *f* connecting the bore *c* with the outer air and, whenever released by the piston *d*, brings the pressure in the bore *c* on the same level as the pressure of the outer air. Therefore, even if compressed air should partly escape from the bore *c* through a leaky joint between the piston 15 *d* and the bore *c* and owing to the leakiness of the stuffing box *h*, it will be filled up again every time before the cushion becomes effective that develops above or below the piston *d* in the bore *c*. At each ascent of the piston rod *e* a cushion will therefore be created 20 as soon as the piston *d* has passed beyond the opening *g* and, vice versa, on passing the opening *f*.

Whenever this happens, the air compressed 25 within the cushion tends to press back the piston *d* with the piston rod *e* into their initial positions, approximately in the center of the length of the bore *c*, and at a speed sufficient to permit the two cushions to be in their 30 proper initial state again for new action during the next blow. This arrangement suffices as a rule for this purpose.

I claim:—

1. A hammer adapted to be raised and accelerated downwardly by an elastic fluid, 35 comprising in combination, a tup, a tup rod with a piston movable within a bore of the tup, an air cushion disposed between the piston of the tup rod and the tup and adapted 40 to become upwardly and downwardly effective during the motion of the piston of the tup rod, and a plurality of ducts through the walls of the tup between the bore of the tup and the outer atmosphere, certain of said 45 ducts being effective above and the others below said piston and adapted to be shut and opened by the piston of the tup rod during its motion within the bore of the tup.

2. A hammer adapted to be raised and accelerated downwardly by an elastic fluid, 50 comprising, in combination, a tup, a tup rod with a piston movable within a bore of the tup, an air cushion disposed between the piston of the tup rod and the tup, and a plurality 55 of ducts through the walls of the tup between the bore of the tup and the outer atmosphere disposed above and below the middle portion of the piston of the tup rod, certain of said ducts being effective above and the 60 others below said piston and adapted to be 65

come shut and opened by the piston of the tup rod during its motion within the bore of the tup.

In testimony whereof I have affixed my 70

ARTHUR SCHNEIDER.
